UNITED STATES PATENT OFFICE.

SOLOMON SACHS, OF WASHINGTON, DISTRICT OF COLUMBIA.

DISPLAY DEVICE.

1,391,583.

Specification of Letters Patent. Patented Sept. 20, 1921.

Application filed April 20, 1921. Serial No. 462,966.

To all whom it may concern:

Be it known that I, SOLOMON SACHS, a citizen of the United States, residing in the city of Washington, in the District of Columbia, have invented a new and useful Display Device, of which the following is a specification.

This invention relates to a novel form of display device, and more particularly to a display device especially designed for supporting forms employed in displaying dresses, suits or the like.

The primary object of the invention is to provide a device of this character which will be continuously rotated, whereby the back as well as the front and sides of the garment may be viewed by a person standing in a position to look into the display window.

A further but important object of the invention is to provide a device which will be adjustable within the window to permit the window to be dressed with facility, the adjustable feature permitting the forms supported by the device to be moved with respect to each other, to vary the positions of the forms within the window.

A further object of the invention is to provide means for supporting the forms to insure the forms being supported in upright positions at all times, and eliminating any possibility of the forms falling from their stands or supports.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a display device constructed in accordance with the present invention, one of the supports or tables shown as removed from its base.

Fig. 2 is an enlarged detail view of an adjustable base showing the manner of supporting the same.

Fig. 3 is a sectional view taken on line 3—3 of Fig. 2; and

Fig. 4 is a transverse sectional view through the shaft housings.

Referring to the drawings in detail, the invention includes a plurality of supports

5 which may be formed of any suitable material and formed in lengths to meet the requirement of usage, the lengths of the supports 5 being determined by the length of 60 the window in which the device is to be positioned. In each support 5 are the openings 6 disposed adjacent to the ends thereof, and designed to accommodate securing screws, whereby the supports may be secured 65 within a window.

Disposed adjacent to one end of each of the supports 5 is a shaft support 7 which also has openings formed adjacent to its ends to accommodate securing screws, the 70 support 7 being also provided with bearings 8 and 9 respectively in which the shaft 10 operates, one end of the shaft 10 being shown as extending beyond the bearing 8 where the same is supplied with a gear 11 75 meshing with the worm 12 formed on one end of the shaft 13 which supports the rotor of the motor 14.

Supported on the shaft 10 are the beveled pinions 15 which are adjustable throughout 80 the length of the shaft 10, the pinions being secured in their positions of adjustment by means of the set screws 16, which pass through openings in the hubs of the pinions 15.

Each of the supports 5 is provided with a bearing 17 secured to the upper surface thereof at points near their ends, the bearings 17 accommodating the ends of the shaft 18 associated therewith. At the end adjacent to the shaft 10 of each shaft 18 is a beveled pinion 19 that meshes with a pinion 15, whereby movement of the shaft 10 is imparted to the shafts 18. Mounted on the supports 5 are the plates 20, each of which 90 is provided with upwardly extending ears 21 which provide supports for the rollers 22 that have portions of their peripheries operating in a plane above the ears 21 where the same contact with the turn-table 23 as 95 associated therewith.

Associated with each plate 20 is an adjustable bearing 24 which is provided with an opening to accommodate the shaft 18, the bearing being provided with openings 105 to accommodate screws 25 which screws are of lengths to extend through the bearing and position themselves in the material of the support. From the foregoing it will be seen that due to this construction, the bearings 24 may be adjusted throughout the 110 lengths of the shafts 18, so that the figure

or forms supported thereby, may be moved to various positions.

A pintle 26 forms a part of each bearing 24 and extends upwardly therefrom, the 5 pintle 26 being accommodated by the openings formed centrally of the turn-tables 23 to hold the turn-tables against movement longitudinally or transversely of the shafts on which they are supported and insure the 10 turn-tables operating in true horizontal planes.

Associated with each turn-table is a friction gear 26' adjustably supported on its shaft to permit the gear to be moved longitudinally of the shaft when the bearings 24 are adjusted, there being provided a suitable securing means passing through the gear 26' to secure the same in its positions of adjustment. A shaft housing 27 is made 20 up of a plurality of sections, the sections being of various lengths to permit the same to be positioned over the shafts 18 when the plates 20 and tables supported thereby are adjusted along the shafts, it being obvious 25 that due to the shape of the housing 27, the same may be positioned directly over a shaft.

In the use of the device, a number of the shafts 18 are positioned within a display 30 window, and the shaft 10 is supported adjacent to one end of each shaft 18, the pinions 15 being adjusted to mesh with the pinions 19 of the shafts 18.

The plates 20 are now adjusted to the 35 required positions along the shafts 18, whereupon the forms are placed on the tables 23. Rotary movement is now transmitted to shaft 10 through the medium of the motor 14 which in turn transmits motion to 40 the shafts 18 and to the tables 23.

From the foregoing it will be obvious that if it is desired to move the supports 5 toward or away from each other to vary the locations of the forms supported thereon, the 45 pinions may be adjusted along the shaft 10 to mesh with the pinions 19 of the shafts 18.

If it is desired to vary the locations of the plates 20, and their turn-tables, it will be seen that the same may be readily shifted to any position along the shaft associated 50 therewith.

It might be further stated that owing to the adjustability of the friction gears 26' along the shafts 18, the gears 26' may be moved independently of each other so that 55 the same will contact with the underside of the tables 23 at any point along the undersurface thereof, thereby causing a number of tables 23 to be operated at various speeds with respect to each other, the main shaft 60 18 on which the gears 26' are supported, being operated at a predetermined speed.

Having thus described the invention, what is claimed as new is:—

1. A display device comprising a shaft, a 65 plurality of plates supported under the shaft, means for securing adjustably the plates to the shaft, each plate having upwardly extending ears, rollers supported on the ears, a table supported above each plate 70 and means for imparting rotary movement of the shafts to the tables.

2. A display device comprising a shaft, plates supported under the shaft, a bearing member supported on the shaft, means 75 for securing the bearing members and plates together, a pintle carried by each bearing member, a turn-table mounted on each pintle, rollers carried by the plates, and adapted to contact with the turn-tables, and means 80 for imparting rotary movement to the shaft and turn-tables.

In testimony that I claim the foregoing as my own, I have hereto affixed my signature in the presence of two witnesses.

SOLOMON SACHS.
